United States Patent Office.

JACOB STEFFE, OF PHILADELPHIA, ASSIGNOR TO FRANCIS BUCKWALTER AND COMPANY, OF ROYER'S FORD, PENNSYLVANIA.

Design No. 3,153, dated August 4, 1868.

DESIGN FOR A COOK'S STOVE.

The Schedule referred to in these Letters Patent and making part of the same.

TO ALL WHOM IT MAY CONCERN:

Be it known that I, JACOB STEFFE, of the city of Philadelphia, in the State of Pennsylvania, have invented or produced a new and original Design for the Plates of a Cook's Stove, of which the following is a full, clear, and exact description, reference being had to the accompanying drawings, making a part of this specification.

My design is for the plates of a cook's stove which, for ready identification, I name "Enola;" and the said design consists of the ornamental configurations A A on the front doors, the ornamental configurations B B on the front plate, the ornamental configurations C C on the respective side doors, and the ornamental moulding D along near the upper edge of the side plate of the said stove, as shown in the drawing.

What I claim as my invention, and desire to secure by Letters Patent, is—

The design for the plates of a cook's stove, herein set forth and shown.
